(57) **CLAIM**

The ornamental design for a shoe sole, as shown and described.

DESCRIPTION

FIG. 1 is a perspective view of a shoe sole, showing my new design;

FIG. 2 is a front view of the shoe sole illustrated in FIG. 1; FIG. 3 is a rear view of the shoe sole illustrated in FIG. 1; FIG. 4 is a side view of the shoe sole illustrated in FIG. 1; FIG. 5 is another side view of the shoe sole illustrated in FIG. 1;

FIG. 6 is a top view of the shoe sole illustrated in FIG. 1; and,

FIG. 7 is a bottom view of the shoe sole illustrated in FIG. 1.

The broken lines in the Figures are for environmental purposes only, and form no part of the embodiment of the claimed design in which they are shown.

1 Claim, 7 Drawing Sheets
